(57) **CLAIM**

We claim the ornamental design for a dining table, as shown and described.

DESCRIPTION

FIG. 1 is a perspective view at a corner of a dining table according to an embodiment of the invention. The perspective view at the opposite corner being the same. The perspective views at the adjacent corners being mirror images thereto.

FIG. 2 is a front elevational view of a dining table according to an embodiment of the invention. The view from the opposite side being the same.

FIG. 3 is a top plan view of a dining table according to an embodiment of the invention; and,

FIG. 4 is an end view of a dining table according to an embodiment of the invention. The view from the opposite end being the same.

The ornamentation on the tops of the legs and along the sides of the table between the table top and lower edge of the table are shown in broken lines and form no part of the claimed design.
